CASING FOR PORTABLE RADIO TRANSCEIVER

Stanford Seiden, North Miami Beach, Fla., assignor to
Sunair Electronics, Inc., Fort Lauderdale, Fla.

Filed Dec. 30, 1971, Ser. No. 214,524

Term of patent 14 years

Int. Cl. D14—03

U.S. Cl. D26—14 L

FIG. 1

FIG. 2

FIG. 1 is a right hand perspective view of a casing for portable radio transceiver, showing my new design.

FIG. 2 is an inverted left hand view thereof.

The broken lines are shown for illustrative purposes only.

I claim:

The ornamental design for a casing for portable radio transceiver, as shown and described.
